ALF SCHAAANNING AND STANLEY AUSTEN STIGANT, OF MANCHESTER, ENGLAND,
ASSIGNORS TO WESTINGHOUSE ELECTRIC AND MANUFACTURING COMPANY, A
CORPORATION OF PENNSYLVANIA.

FUSE.

1,212,694.

Specification of Letters Patent. Patented Jan. 16, 1917.

Application filed December 2, 1916. Serial No. 134,630.

To all whom it may concern:

Be it known that we, ALF SCHAAANNING, a subject of the King of England, and a resident of Manchester, in the county of 5
5 Lancaster, England, and STANLEY AUSTEN STIGANT, a subject of the King of England, and a resident of Manchester, in the county of 10
10 Lancaster, England, have invented a new and useful Improvement in Fuses, of which
10 the following is a specification.

Our invention relates to fuses for protecting electric circuits and particularly to fuses of the horn type that are designed, primarily, for the protection of the high- 15
15 tension windings of transformers.

One object of our invention is to provide an improved fuse that shall be particularly suitable for use in outdoor installations, the device being unaffected by rain, snow, sleet 20 or ice.

Another object of our invention is to provide a fuse of the above indicated character having means whereby the replacing of a broken fusible conductor may be easily effected. 25

According to our invention, the device comprises a central member of insulating material, preferably porcelain, to the ends of which metal pieces, having converging- 30
30 diverging arcing horns thereon, are attached by suitable clips. A fusible conductor or wire is attached to the said metal pieces by winding the same around the arcing horns at the narrowest part of the gap therebetween. The metal end pieces are provided with hollow conical portions by which the entire device is supported on the upwardly 35
35 extending portions of two L-shaped rods constituting the terminals of the circuit to be protected, said rods being carried by suitable insulators. The hollow conical portions are provided with downwardly extending portions constituting V-shaped notches that so engage the horizontal portions 40
40 of the supporting rods as to guide the device while it is being placed in position.

In the accompanying drawings, Figure 1 is a side view, partially in section and partially in elevation, of a protective fuse device embodying our invention, and Fig. 2 is a sectional view taken on the line II-II of Fig. 1. 50
50

In Fig. 1 of the drawings, the central por-

tion of the device comprises a porcelain insulator 1 of bobbin-shape, having cylindrical ends 2. Metal members 3 are provided with semi-circular portions 4 to which caps 5 are so secured by bolts 6 as to grip the cylindrical portions 2 of the insulator. Arcing horns 7 are secured in sockets 8 in the metal members 5 and are maintained in the same vertical plane by fins or guides 9 on the metal members 3. A fusible wire or conductor 10 is secured, at its ends, to the members 3 by screws and nuts 11 and is so wrapped around the arcing horns 7, as indicated at the points 12, as to open the arc gap at its narrowest part. The members 3 are provided with hollow conical portions or cups 13 that are adapted to engage the upwardly extending portions or legs 14 of L-shaped rods, the horizontal portions 15 of which are clamped between the two halves of caps 16 that are mounted on insulators 17 which, in turn, may be supported from a suitable bar 18. The rods 15 constitute the terminals of the fuse device, and the circuit to be protected may be connected to the ends thereof in any suitable manner. The hollow conical portions 13 are provided with downward extensions 19 constituting V-shaped notches that, when the device is to be placed in position, engage the horizontal portions 15 of the rods and cause the insides of the cones 13 to engage the points 20 of the upwardly extending portions of the rods 14, by which means the device is guided to a correct position in which the plane of the arcing horns 7 is substantially vertical. By this construction, the central portion is 25
25 made completely self-aligning.

When it is desired to replace a broken fusible conductor the entire device is removed from the supporting rods 15 in order that the fusible conductor may be replaced at leisure and without danger of shock. Another advantage is that an isolating switch for disconnecting the device from the line is not required. For the removal and subsequent replacement of the device an insulating pole of wood or other suitable material having a spring clip, the jaws of which are adapted to engage the central part 1, may be employed, thereby making it unnecessary to touch the fuse device. 100
100
105

Our invention is not limited to the par-

ticular structure illustrated as it may be variously modified without departing from the spirit and scope of the invention as set forth in the appended claims.

5. We claim as our invention:

1. The combination with an insulator having a conducting cup member mounted on each end thereof, of horn members operatively connected to the cup members and 10 adapted to receive a fusible conductor.

2. The combination with stationary terminal members, of an insulator having a conducting cup at each end thereof to receive the stationary terminal members, and 15 means for securing a fusible conductor to the said cups.

3. The combination with stationary terminal members, of an insulator of substantially bobbin shape, a conducting cup secured to each end of the insulator having means for receiving the said terminal members, a horn member secured to each of the conducting cups, and a fusible conductor connected between the horn members.

25. 4. The combination with upwardly extending terminal members, of conical conducting cups for receiving the terminal members, an insulating member for securing

the cups together, horn gap members secured to the said cups, and a fusible conductor so secured to the horn gap members.

5. The combination with two stationary insulators, and upwardly extending contact members mounted thereon, of an insulating member having horn gap members mounted 35 thereon, and means secured to each end of the insulating member whereby the horn gap members are maintained in a predetermined position and in electrical connection with the upwardly extending contact members.

6. The combination with stationary terminal members, of an insulating member, horn gap members, a fusible conductor connected between the horn gap members, and 45 means for guiding and securing the horn gap members in effective engagement with the stationary terminal members.

In testimony whereof, we have hereunto subscribed our names this thirteenth day of November, 1916.

ALF SCHAANNING.

STANLEY AUSTEN STIGANT.
